Specification of Letters Patent.

Patented May 4, 1915.

Application filed July 20, 1912. Serial No. 710,566.

To all whom it may concern:

Be it known that we, JOHN H. SHAW and ALBERT A. PAGE, of the city of New Haven and town of East Haven, respectively, county of New Haven, and State of Connecticut, have invented new and useful Improvements in Locks, of which the following is a full, clear, and exact description.

This invention relates to locks, and particularly to locks embodying a latch bolt which can be deadlocked by means of a thumb turn or similar instrumentality at the inside of the door.

The primary objects of the invention are to provide improved means for deadlocking the latch bolt by means of a thumb turn, or the like; to furnish a lock having thumb turn operated deadlocking means for the latch bolt which can be withdrawn from its deadlocking position by means of a certain key called an emergency key insertible in the lock to retract the latch bolt; and to provide a lock in which the deadlocking means for the latch bolt is movable into operative position by said emergency key in order to block the latch bolt against operation by the other key or keys.

Other objects of the invention are to furnish an improved combination of mortise lock mechanism with a cylinder lock mechanism of the master-keyed type; and to improve the general construction and operation of locks of the class to which our invention relates.

With these and other objects in view, the invention consists in the novel features and combinations of parts to be hereinafter described and pointed out in the claims.

In the accompanying drawings, illustrative of a preferred embodiment of the invention, Figure 1 is an elevation of the lock, with the cap plate removed, showing the latch bolt free to be retracted by either knob or by any of the series of keys; Fig. 2 is a similar view, showing the latch bolt deadlocked by means of the thumb turn, so that the knobs and certain keys are inoperative to retract it; Fig. 3 is a detail view of a portion of Fig. 2, illustrating the action of the emergency key in withdrawing the deadlocking slide from the path of the bolt; Figs. 4 and 5 are sections, through the complete lock, taken on line 5—5 of Fig. 2, Fig. 4 showing the operation of the change key, and Fig. 5 showing the operation of the

emergency key; Fig. 6 is a rear face view of the cylinder lock; Fig. 7 is a horizontal section through the rear portion of the cylinder lock; Fig. 8 is a detail edge view of the deadlocking slide; and Fig. 9 shows the master and grand master keys.

The lock case 10, shown in the drawings, having the face plate 11, contains a latch bolt 12, normally protracted by means of a spring 13, and having at the end of its stem 14 a cross-head 15. In the embodiment illustrated, the bolt is retracted by means of a yoke 16, and inner and outer roll-backs 17, 18, respectively. The outer roll-back 18 preferably has associated with it night latch mechanism of the usual type, comprising a dogging slide 19, a releasing slide 20, and a connecting lever 21.

The latch bolt 12 is retracted by means of a key inserted at the outside of the lock, through the intermediary of an elbow lever 22, pivoted in the case at 23, and having a depending arm 24 coacting with the cross-head 15 of the latch bolt. The other arm 25 of the elbow lever 22 is adapted to be depressed by the bit of a cylinder lock, as hereinafter described, whereby the arm 24 of said lever is carried rearwardly, thereby retracting the latch bolt.

The parts so far described are of well known form, and do not constitute in themselves essential features of the present invention.

According to this invention, the latch bolt 12 is adapted to be deadlocked in its protracted position by means of a thumb turn, or the like, at the inside of the door. In the lock shown in the drawings, a thumb turn hub 26 is mounted for oscillatory movement in the walls of the case, as shown in Figs. 1 and 5, said hub having its ends 26a formed as trunnions, having bearings in the cap plate and bottom, respectively, of the case. The opening through the hub 26 is preferably of square cross-section to accommodate a thumb turn spindle (not shown) of the usual form. Projecting from the thumb turn hub is an arm 27 adapted to move in a vertical direction a slide 28 suitably guided in the case, and having a projection 29 to extend in the rear of the latch bolt cross-head 15 in order to deadlock the latch bolt.

In the form shown, the arm 27 of the thumb turn hub fits between pins or abutments 30, 31, projecting from the deadlock-

- ing slide 28, so that if the arm 27 is moved downward it will abut the pin 31 and thereby move the slide to deadlocking position, whereas if the arm is moved upward it will 5 abut the pin 30, and thereby remove the deadlocking slide from the path of the latch bolt. The slide may be guided in the case between the rear wall 32 of the same and a projection 33, which projection also serves 10 as a stop, cooperating with a shoulder 34 on the slide to prevent the downward movement of the slide beyond the position shown in Fig. 2, *i. e.*, below its proper deadlocking position. After the slide has been moved to 15 its operative or inoperative position, it is held firmly in such position by the frictional engagement with the cap piece of a small coiled spring 35, socketed in the projection 31.
- 20 The key operated means for moving the deadlocking slide comprises a disk 36 mounted for oscillation in one wall of the case, and carrying a dog or rollback 37, having an arm 38, projecting freely into the space 25 between the pins 39, 40 on the deadlocking slide. The relation of the dog arm 38 to the pins 39, 40, is similar to that of the thumb turn arm 27 to the pins 30 and 31, so that if the arm 38 is depressed, as shown 30 in Fig. 2, it will move downward the deadlocking slide, while if said arm is raised, as shown in Fig. 3, it will raise the deadlocking slide into inoperative position.
- 35 The slide operating dog 37 is shown as being located in that wall of the case which is at the inside of the door, and it is in substantial alinement with a cylinder lock 41 (Figs. 4 and 5), by means of which the latch bolt retracting lever 22 is operated. This 40 cylinder lock comprises the cylinder 42, a sleeve 43 rotatable therein, a plug or barrel 44 rotatable in said sleeve, and the usual tumbler pins 45. The particular construction of these parts is not material to the 45 present invention, but in the form shown it is intended that the plug or barrel 44 be operable alone by means of the ordinary or change key 46, Fig. 4, while the master key 47, grand master key 48, and emergency key 49, are adapted to rotate the barrel and the sleeve together, substantially as indicated in 50 Fig. 5. A dog 50 applied to the rear end of the plug or barrel 44 has its bit 51 engaged in a guide-way 52 in the bit 53 of a ring or dog 54 rotatably mounted on the rear end of the sleeve 43. As the barrel 44 is always rotated by each key of the series, (either about its own axis or about the axis of the sleeve 43) and as the dogs 50, 54, are locked 55 together in the manner specified, it will be obvious that the dog 54 is adapted to be oscillated by all of the various keys. The rotation of the dog 54 in the proper direction will cause its bit 53 to strike the free 60 end of a lever 55, pivoted in the case at 56,

and resting freely on the arm 25 of the latch bolt retracting lever 22. Hence, if the deadlocking slide 28 is in its raised inoperative position, permitting the latch bolt to be retracted, such an operation of the cylinder 70 lock will cause the arm 25 of the latch bolt lever to be depressed, thereby swinging said lever on its pivot and retracting the latch bolt.

In order to enable the door to be opened 75 from the outside in spite of the deadlocking of the latch bolt from the inside by means of the thumb turn hub 26, the emergency key 49, Fig. 5, must act on the dog 37 in such a manner as to retract the slide from 80 its deadlocking position. In order to attain this end, the deadlocking dog or rollback 37 is provided with a cut-away portion 36^a adapted to be engaged by a suitable part of the cylinder lock which is projected into 85 said cut-away portion or recess only by means of the emergency key. In the embodiment shown, the dog 37 is engageable by a slide 57 movable longitudinally in the rear portion of the cylinder lock 41, as 90 shown in Figs. 4 and 5. This slide is guided in an extension of the keyhole, as shown in Fig. 7, and it is of suitable form to prevent it from being projected out of the lock cylinder beyond the position shown in Fig. 5. 95 The slide 57 is normally held by means of a coiled spring 58 with its rear end substantially flush with guide flanges 59 projecting rearward from the cylinder lock and between which said slide is confined, as 100 shown in Fig. 7. When a change key 46, master key 47, or grand master key 48, is inserted into the lock, the pointed end of the same will take into a correspondingly formed cut-away portion or recess 60 in the 105 inner edge of the slide 57, and said slide will therefore remain in its retracted position. The emergency key 49, however, is provided with a squared off extremity 61 which does not fit the recess 60, but, on the other hand, 110 comes in full contact with a portion of the edge of the slide 57, so that the latter is thereby protracted to a certain extent, as shown in Fig. 5, into a position wherein it extends into the recess 36^a of the dog 37. 115

The operation of the lock is substantially as follows: If the thumb turn hub 26 is raised into the position shown in Fig. 1, the slide 28 will be lifted out of the path of the latch bolt 12, and it will therefore be 120 possible to retract the latch bolt by means of the inner knob and its roll-back 17, and, in case the dogging slide 19 is in inoperative position, by the outer knob and its roll-back 18. The latch bolt is also freely retractable 125 by any of the series of keys, under these conditions, the bit 53 of the cylinder-lock dog or rollback 54 being movable into a position in which it depresses the arm 25 of the latch bolt lever and retracts the latter. Suppos- 130

ing, now, that the thumb turn hub be operated from the inside of the room and shifted to the position shown in Fig. 2, the deadlocking slide 28 will be moved downward 5 against the stop 35, the projection 29 being then located immediately in the rear of the cross-head 15. It will then be impossible to retract the latch bolt by means of either roll-back, or by means of the change, master 10 or grand master keys, the yoke 16 and the latch bolt lever 22 being effectively deadlocked by the deadlocking of the latch bolt itself. The emergency key, however, will still unlock the door from the outside owing 15 to the fact that the slide 57 of the cylinder lock will be operated by said emergency key, as hereinbefore described, so that said slide while in engagement with the recess 36^a of 20 the dog 37, will be rotated bodily with the rotating parts of the cylinder lock. As said 25 slide is rotated from its normal upright position (Fig. 5) into the inclined position shown in Fig. 3, it will be so brought into contact with the walls or edges of the recess 36^a as to shift the dog 37 in the direction of 30 the arrow, Fig. 3, thereby raising the slide 28 toward its inoperative position. By the time the bit 53 of the cylinder lock abuts the lever 55 preparatory to the actuation of the latch bolt lever, the deadlocking slide will 35 be substantially removed from the path of the latch bolt, and as the emergency key is further rotated to an extent sufficient to retract fully the latch bolt, the deadlocking slide will simultaneously be raised to clear entirely the inwardly moving latch bolt.

The timing of the operations of the slide 57 and bit 53 may of course be varied somewhat as desired, it merely being necessary 40 that as the latch bolt moves inward the deadlocking slide be in a position to permit an unobstructed incursion of the bolt.

It will be noted that inasmuch as the dog 37 is capable of shifting the deadlocking 45 slide in either direction, said slide may be moved from inoperative into operative position from the outside of the door by the use of the emergency key. In order to effect this result, the emergency key is inserted in the 50 cylinder lock and rotated in a clockwise direction, thereby shifting the slide 28 downward into its deadlocking position, as shown in Fig. 2. When the parts have reached the 55 position just indicated, further movement of the slide, dog, and key will be prevented by the engagement of the stop lug 33 with the stop shoulder 34 of the slide. The cutaway portion 36^a of the dog 37 is of such form, however, as to permit the emergency key to 60 be turned back into a position in which it can be removed from the cylinder lock. If any of the other keys of the series is then inserted into the cylinder lock, it will be inoperative to retract the latch bolt. The 65 latch bolt may therefore be deadlocked

against a certain key or keys by the use of another key at the same side of the door as well as by a thumb-turn member or the like on the opposite side of the door.

While the foregoing description is a detailed one, in so far as it concerns the particular embodiment of our invention selected for illustration, it will be understood that the invention is susceptible of numerous other embodiments within the scope of the appended claims.

We do not claim the cylinder lock mechanism *per se*, as the same is the invention of Frank I. Kimball, as claimed in his application Serial No. 805,065, filed December 6, 1913.

What we claim is:

1. In a lock, the combination of a case, a latch bolt therein, a deadlocking slide movable substantially at right angles to the latch bolt, and adapted to deadlock the same, a cylinder lock mechanism carried by the case embodying two rollbacks, a latch-retracting lever pivoted to the case and adapted to be actuated by one of said rollbacks, the second rollback being arranged to move said deadlocking slide into and out of operative position, a key for operating said first rollback to retract the latch bolt, and a second key for actuating both rollbacks to withdraw 95 said deadlocking slide from operative position, and then immediately retract the bolt on the same movement of the key; substantially as described.

2. In a lock, the combination of a case, a latch bolt therein, a deadlocking slide movable substantially at right angles to the latch bolt and adapted to deadlock the same, a retracting lever for said latch bolt pivoted to the case, a cylinder lock mechanism carried by the case and having two rollbacks, one of said rollbacks being adapted to operate said retracting lever, and the other rollback being adapted to operate said deadlocking slide, said rollbacks being substantially in line with each other and located in the space between said deadlocking slide and the free end of said retracting lever, a key for operating the latch-retracting rollback individually, and a second key for coupling said rollbacks together, and for withdrawing the deadlocking slide from operative position and retracting the bolt within less than a full rotation of the key in one direction; substantially as described.

3. In a lock, the combination of a case, a latch bolt therein, a deadlocking slide for said latch bolt slidable at right angles to the latter, a retracting lever for the latch bolt pivoted in the case, a cylinder lock mechanism carried by the case and having a rollback adapted to actuate said retracting lever, said rollback normally having an upright position, a second or emergency rollback for said cylinder lock mechanism posi-

- tioned operatively with respect to said deadlocking slide, and extending at an angle to the first rollback, a key for actuating the first rollback to retract the latch bolt, and a second key for actuating both rollbacks together to move said slide into deadlocking position, or to withdraw the slide from deadlocking position, and then retract the latch bolt on further movement of the key 10 substantially as soon as the slide is moved out of the path of said bolt; substantially as described.
4. In a lock, a latch bolt, a deadlocking slide movable at right angles thereto, a retracting lever for said latch bolt, a cylinder lock mechanism having two rollbacks, a key for actuating one of said rollbacks to operate said retracting lever and withdraw the bolt, means for moving said slide into deadlocking position, and a second key for moving the deadlocking slide out of operative position by means of the second rollback, and for retracting the latch bolt by the first rollback, while the slide is being withdrawn 20 from operative position; substantially as described.
5. In a lock, the combination of a case, a latch bolt therein, a deadlocking slide movable at right angles to the latch bolt, a thumb turn hub for moving said slide into and out of deadlocking position with respect to the latch bolt, a retracting lever for the bolt pivoted in the case, a cylinder lock mechanism cut of line with said thumb turn 30 hub, and having two rollbacks located in the space between said deadlocking slide and the free end of said retracting lever, a key for actuating one of said rollbacks to operate said retracting lever and withdraw the bolt, 40 and another key for operatively actuating the second rollback, in addition to the first, and for withdrawing the deadlocking slide from operative position prior to the retraction of the bolt on the same movement of the key; substantially as described.
6. The combination with lock mechanism, of a pin tumbler lock having a key plug, said key plug provided with a keyway, a rollback for operating said lock mechanism 50 connected with the rear end of the key plug, a second rollback, a plurality of keys insertible into said keyway, and a slide in said keyway movable relative to said first rollback by only one of said keys, and adapted 55 to actuate said lock mechanism by means of said second rollback; substantially as described.
7. The combination with lock mechanism, of a pin tumbler lock having a key plug, said key plug provided with a keyway, a rollback connected with the rear end of the key plug, and adapted to operate a part of 60 said lock mechanism, a second rollback, a plurality of keys insertible into said keyway, and a slide movable relative to said 65
- first rollback by engagement with one of said keys, and adapted when so moved to operate another part of said lock mechanism by means of said second rollback when said key is rotated, said slide being operative by another of said keys; substantially as described.
8. The combination with a mortise lock having a case and two separate parts or members therein, of a pin tumbler lock having a key plug, said key plug provided with a keyway, a rollback connected with the rear end of the key plug, and adapted to operate one part or member of said mortise lock, a second rollback adapted to operate another part or member of said mortise lock, a plurality of keys insertible into said keyway, and a sliding member shiftable longitudinally of the keyway by one of said keys but not by another key, and adapted when so shifted to operate the second-hand part or member of said mortise lock by means of said second rollback; substantially as described.
9. The combination with a mortise lock mechanism having two parts or members, of a cylinder lock having a keyway, a key insertible into said keyway, another and different key insertible into said keyway, a rollback carried by said cylinder lock to operate with one of said parts or members, and operable by both of said keys, and a slide projecting into the rear of the keyway, and movable rearwardly by engagement with one of said keys into coöperation with said other part or member of said mortise lock mechanism, said key-engaging slide being inoperative by said other key; substantially as described.
10. A cylinder lock having a key plug, said key plug provided with a keyway, a change key insertible into said keyway, an emergency key insertible into said keyway, a rollback operatively connected with said key plug and rotatable by both of said keys, and a spring-pressed slide projecting into the rear end of the keyway, and movable rearwardly by said emergency key, said slide being substantially immovable by said change key, in combination with a mortise lock mechanism having a part to coöperate with said rollback, and another part to coöperate with said slide; substantially as described.
11. A cylinder lock having two keys, a rollback operable by both of said keys, and a coupling slide forming a part of said cylinder lock, and slidably by one of said keys but not by the other key, in combination with a lock mechanism having a part to coöperate with said rollback, and another part to coöperate with said coupling slide; substantially as described.
12. A cylinder lock having a keyway, two keys insertible into said keyway, and of

substantially the same over-all length, a slide extending into the keyway from the rear of said cylinder lock, and movable by one of said keys but not by the other of said keys, and a rollback operable by both of said keys, in combination with lock mechanism having a part to coöperate with said slide, and another part to coöperate with said rollback; substantially as described.

18. A pin tumbler lock having a key plug, 70 said key plug provided with a keyway, a rollback connected with the rear end of the key plug, a second rollback, a plurality of keys insertible into said keyway, lock mechanism, and a slide movable relative to said first rollback by only one of said keys, and adapted to actuate said lock mechanism by means of said second rollback; substantially 75 as described.

19. A cylinder lock having a keyway, a 80 rearwardly movable slide in the rear portion of said keyway, for operating a part outside of said cylinder lock, said slide normally retracted with respect to said keyway, a key formed to shift said slide rearwardly 85 as the key is inserted into the keyway, and another key fully insertible into the keyway without shifting said slide, in combination with a lock mechanism having a part in operative association with the key plug, 90 when said slide is retracted, and another part adapted to be operated by said slide when the same is moved rearwardly by said first-named key; substantially as described.

20. A cylinder lock having a rearwardly 95 movable slide mounted in the rear end portion of the keyway, a key insertible into said keyway to shift said slide rearwardly, a second key fully insertible into said keyway 100 without shifting said slide, and a spring 105 to return said slide to a definite normal position when said first key is withdrawn, in combination with a lock mechanism having a part operatively associated with said cylinder lock when said slide is in its normal 110 position, and another part to coöperate with said slide when the latter is moved rearwardly by said first-named key; substantially as described.

21. The combination with a mortise lock 110 mechanism, of a cylinder lock having a key plug, said key plug provided with a keyway, a change key insertible into said keyway, an emergency key insertible into said keyway, a rollback operatively connected with 115 said key plug and rotatable by both of said keys, and a slide projecting into the rear end of the keyway, and movable rearwardly by said emergency key into position to operate a part of said mortise lock mechanism, 120 said member being immovable into operative position by said change key; substantially as described.

22. A cylinder lock having two keys, a 125 rollback operable by both of said keys, and a slide to operate a part outside and at the rear of said cylinder lock, operative by one of said keys but not by the other key, in combination with a mortise lock mechanism having a part to coöperate with said roll- 130

5 substantially the same over-all length, a slide extending into the keyway from the rear of said cylinder lock, and movable by one of said keys but not by the other of said keys, and a rollback operable by both of said keys, in combination with lock mechanism having a part to coöperate with said slide, and another part to coöperate with said rollback; substantially as described.

10 13. In a lock, the combination of a latch bolt, a retracting mechanism therefor, a deadlocking mechanism therefor, a pin tumbler lock having a key plug, said key plug provided with a keyway, a rollback for operating one of said first-named mechanisms, connected with the rear end of the key plug, a second rollback, a plurality of keys insertible into the keyway, and a member movable relative to said first rollback by only one of said keys, and adapted to actuate the other of said two mechanisms by means of said second rollback; substantially 15 as described.

14. In a lock, the combination of a latch bolt, a retracting member therefor, a member for dogging said bolt in a definite position, a pin tumbler lock having a key plug, said key plug provided with a keyway, a rollback for operating one of said first-named members, connected with the key plug, a second rollback, a plurality of keys insertible into said keyway, and a slide in the keyway movable relative to said first rollback by only one of said keys, and adapted to actuate the second of said first-named members by means of said second rollback; substantially 20 as described.

15. In a lock, the combination of a latch bolt, a retracting lever therefor, a deadlocking 40 slide for said bolt, a pin tumbler lock having a key plug, said key plug provided with a keyway, a rollback for operating said retracting lever, connected with the rear end of the key plug, a second rollback, a plurality of keys insertible into said keyway, and a member movable relative to said first rollback by only one of said keys, and adapted to actuate said deadlocking slide by means of said second rollback; substantially 45 as described.

16. A pin tumbler lock having a key plug, said key plug provided with a keyway, a rollback connected with the rear end of said key plug, and a key-engaging slide in the keyway, in combination with a mortise lock mechanism having a part to coöperate with said rollback, and a part to coöperate with said slide; substantially as described.

17. A pin tumbler lock having a key plug, 55 said key plug provided with a keyway, a rollback connected with the rear end of the key plug, a second rollback, and a spring-pressed key-engaging slide for actuating the second rollback movable relative to the first rollback, in combination with a mortise lock 60 mechanism having a part to coöperate with said roll-

back, and a second part into coöperation with which said slide is movable by said first-named key; substantially as described.

23. A cylinder lock having a key plug, 5 said key plug provided with a keyway, pin tumblers coöoperating with said key plug, a key insertible into said keyway to rotate said key plug, another and different key insertible into said keyway to rotate said 10 key plug, and a slide adapted to project out of the rear end of said cylinder lock, and having a part extending into said keyway, and movable rearwardly by one of said keys but not by the other key, in combination

with a lock mechanism having a part in co-operative association with said cylinder lock when said slide is in its forward position, and another part adapted to coöperate with said slide when the latter is moved rearwardly; substantially as described. 15 20

In witness whereof, we have hereunto set our hands on the 19th day of July, 1912.
